CLAIM

The ornamental design for a display screen or portion thereof with animated graphical user interface as shown and described.

DESCRIPTION

FIG. 1 is a front view of a display screen or portion thereof with a first image of an animated graphical user interface in accordance with a first embodiment of our new design; FIG. 2 is a front view thereof with a second image of the animated graphical user interface;

FIG. 3 is a front view thereof with a third image of the animated graphical user interface;

FIG. 4 is a front view of a display screen or portion thereof with a first image of an animated graphical user interface in accordance with a second embodiment of our new design; FIG. 5 is a front view thereof with a second image of the animated graphical user interface;

FIG. 6 is a front view thereof with a third image of the animated graphical user interface;

FIG. 7 is a front view of a display screen or portion thereof with a first image of an animated graphical user interface in accordance with a third embodiment of our new design; FIG. 8 is a front view thereof with a second image of the animated graphical user interface;

FIG. 9 is a front view thereof with a third image of the animated graphical user interface;

FIG. 10 is a front view of a display screen or portion thereof with a first image of an animated graphical user interface in accordance with a fourth embodiment of our new design; FIG. 11 is a front view thereof with a second image of the animated graphical user interface;

FIG. 12 is a front view thereof with a third image of the animated graphical user interface;

FIG. 13 is a front view of a display screen or portion thereof with a first image of an animated graphical user interface in accordance with a fifth embodiment of our new design; FIG. 14 is a front view thereof with a second image of the animated graphical user interface;

FIG. 15 is a front view thereof with a third image of the animated graphical user interface;

(Continued)

FIG. 16 is a front view of a display screen or portion thereof with a first image of an animated graphical user interface in accordance with a sixth embodiment of our new design; FIG. 17 is a front view thereof with a second image of the animated graphical user interface; and,

FIG. 18 is a front view thereof with a third image of the animated graphical user interface.

The outermost broken lines in the figures show a display screen or portion thereof, and form no part of the claimed design. The appearance of the graphical user interface of each embodiment transitions sequentially between FIGS. 1-3, 4-6, 7-9, 10-12, 13-15, and 16-18 respectively. The process or period in which one image transitions to another forms no part of the claimed design.
